US0D1080543S

(12) **United States Design Patent** (10) **Patent No.:** **US D1,080,543 S**
(45) **Date of Patent:** **** Jun. 24, 2025**

(54) **COIL COMPONENT**

(71) Applicant: **TDK CORPORATION**, Tokyo (JP)

(72) Inventors: **Chen Wang**, Tokyo (JP); **Satoshi Sugimoto**, Tokyo (JP)

(73) Assignee: **TDK CORPORATION**, Tokyo (JP)

(**) Term: **15 Years**

(21) Appl. No.: **29/847,700**

(22) Filed: **Jul. 27, 2022**

Related U.S. Application Data

(62) Division of application No. 29/754,321, filed on Oct. 9, 2020, now Pat. No. Des. 964,281.

(30) **Foreign Application Priority Data**

Apr. 10, 2020 (JP) ..... 2020-007586 D

(57) **CLAIM**

The ornamental design for a coil component as shown and described.

DESCRIPTION

FIG. 1 is a front elevation view of a first embodiment of the coil component;

FIG. 2 is a rear elevation view thereof;

FIG. 3 is a left-side elevation view thereof;

FIG. 4 is a right-side elevation view thereof;

FIG. 5 is a top plan view thereof;

FIG. 6 is a bottom plan view thereof; and

FIG. 7 is a perspective view thereof.

FIG. 8 is a front elevation view of a second embodiment of the coil component;

FIG. 9 is a rear elevation view thereof;

FIG. 10 is a left-side elevation view thereof;

FIG. 11 is a right-side elevation view thereof;

FIG. 12 is a top plan view thereof;

FIG. 13 is a bottom plan view thereof; and,

FIG. 14 is a perspective view thereof.
